HINGE CONSTRUCTION

Charles E. Campbell, South Bend, Ind., assignor
of one-tenth to Walter E. Schirmer, Buchanan,
Mich.

Application March 18, 1940, Serial No. 324,577

12 Claims. (Cl. 16—147)

This invention relates to hinge constructions, and more particularly is directed to a hinging arrangement for doors of refrigerators, cabinets, lockers, and other analogous closure members in which it is desirable that the door be capable of swinging open from either vertical edge.

It is commonly known that in connection with the domestic mechanical refrigerators of well known types, care must be exercised by the purchaser to insure that the door swing in the proper direction for the location in the home where the refrigerator is placed. In other words, the purchaser must specify either a right hand or left hand door, depending upon the location. This requires that the manufacturer carry both types of doors in stock and that the refrigerator, as a whole, be designed so that either type of door can be readily mounted thereon.

However, the main objection outside of the cost of duplicating this mechanism, is the fact that the purchaser may desire to move the refrigerator to a new location in which the door may not be conveniently swung in the desired manner. This results in an awkward arrangement, and may necessitate many extra steps daily by the user of the refrigerator.

The same objections are of course true in connection with cabinets, lockers and similar structures where it is desired that entrance may be had to the same from either side of the door opening, this sometimes being impossible with the present types of constructions.

It is therefore a primary object of the present invention to provide a hinge structure of this general class in which the door may be swung open from either vertical edge; that is to say, duplicate hinging arrangements are provided on each vertical edge of the door, these being simple and rugged in construction, whereby the door may be opened in either direction without disturbing the hinging arrangement and without imposing any undue stresses on the structure.

In accomplishing this object, one of the prime factors in the development of the present construction is to provide a hinge structure that would be capable of adaptation to the customary type of door now in use so that little or no change would be required in the dies now employed in forming such doors and door openings, and allowing ready conversion of equipment now manufactured to the present construction.

In developing a construction of this type, one of the fundamental principles involved was to provide a hinge arrangement which, when the

door edge was engaged or latched thereto, would rigidly support the door in a vertical direction and would securely lock the door against withdrawing movement from the hinge so that the hinge structure could function in the desired manner as a hinge whenever its corresponding door edge was secured in locked engagement therewith. At the same time, however, the design was arranged so that upon release of the simple locking mechanism, the door edge could easily swing away from the associated hinge and move into a position normal to the plane of the door opening to allow full access to the interior of the compartment which the door closed.

Still another object accomplished by the present invention resides in the provision of a construction which produces a positive seal about the door to prevent any thermal losses therethrough. Due to the novel type of hinging structure, it was necessary that the sealing means be given special attention to insure that an adequate seal would be present when the hinge was functioning as a support for the door edge, and also when the door was unlatched from the hinge.

Another object of the present invention was to provide a construction in which the hinge and the associated engaging parts of the door proper should all be made from simple stampings of flat plate or the like whereby the cost of manufacture could be kept within the desired range and not render the use of the construction prohibitive.

With these and other objects and advantages in mind, it is believed that the present invention will be more clearly understood by those skilled in the art by reference to the accompanying drawings and specification forming a part hereof, which disclose in detail the construction and operation of preferred forms of the invention.

In the drawings:

Figure 1 is a partial perspective view of a door opening provided with a hinge structure of the present invention;

Figure 2 is a perspective view with portions broken away of a door engageable with the hinge structure shown in Figure 1;

Figure 3 is a transverse sectional view of the door structure in closed position;

Figure 4 is a detailed sectional view taken on line 4—4 of Figure 1;

Figure 5 is an enlarged detail view of the latching mechanism shown in Figure 3;

Figure 6 is a perspective view of a modified form of hinge structure;

Figure 7 is a side elevational view of the hinge structure of Figure 6 with the door in engagement therewith;

Figure 8 is a sectional view taken substantially on line 8—8 of Figure 7;

Figure 9 is a sectional view taken substantially on line 9—9 of Figure 7;

Figure 10 is a perspective view of a door structure for use with the hinge of Figure 6;

Figure 11 is a sectional view through a still further modified form of hinge structure;

Figure 12 is a sectional view taken on line 12—12 of Figure 11;

Figure 13 is a detail view of the upper end of the hinge structure shown in Figure 11; and

Figure 14 is a transverse sectional view through a further modified form of construction.

Referring now in detail to the form of the invention shown in Figures 1 to 5, inclusive, a door opening is indicated generally by the reference numeral 5 and is bound at its lateral edges by vertically extending walls 6, as shown in Figure 3. Secured on the walls 6 are substantially identical hinge structures comprising the angle members 7 which seat in recessed face portions of the edges 6 of the door opening and are secured therein by means of screws or the like indicated diagrammatically at 8. Projecting normally from the planar portions of the members 7 secured in the recess of the door edges are flange portions which, at their outer ends, are reversely curved as indicated at 9 in Figure 1 to fit about a vertically extending hinge pin 10 which is disposed slightly outwardly of the plane of the door opening.

The hinge pins 10 therefore extend for substantially the full height of the door opening, and on opposite sides of the portions 9 are engaged by the reversely turned portions 12 of the movable portion 13 of the hinge assembly. This movable portion comprises a sheet metal stamping which may be plated if desired, which extends parallel to the secured portions of the hinge plate 7 but spaced forwardly thereof to form an elongated gap therebetween which is normally sealed by a suitable resilient sealing member 14 of any desired or preferred construction. The member 13 is then provided with a channel-shaped portion extending at right angles to the sealed portion and having the defining walls 15 and 16 spaced apart to define a channel-shaped recess 17 which is closed at its inner end by the transversely extending web portion 18. This channel is so arranged that the wall 15 thereof, when in normal position, lies against the defining surface of the vertical walls 6 of the door opening and the channels therefor extending vertically along opposite sides of the door opening. The blank from which the channel is formed is provided with tabs at the upper and lower portions of the wall 16 which are folded inwardly into the channel, as indicated at 19 in Figures 1 and 4, and may be spot welded to the adjacent surface of the wall 15 if so desired. The tabs or spacing portions 19 in the channel preferably have angularly inclined edges 20 which converge toward the rear end or closed end of the channel for a purpose to be hereinafter described.

It will be apparent with the construction thus far described that the portion 13 of the hinge assembly is free to rotate about the hinge pin 10 into and out of the door opening, but when alined against the side walls of the door opening, the member 13 presses against the sealing strips 14 in such manner as to provide a thermal insu-

lating seal between the defining wall of the door opening and the hinge construction.

Considering now the door structure adapted to be received within the hinges, the door comprises an outer closure member 25, which may be lacquered or enameled in any suitable manner, provided with reentrant portions 26 forming a smooth bead or edging entirely around the door. Secured on the surfaces of the reentrant portions 26 is a body member 27 of generally rectangular form, which is offset inwardly from the plane of the reentrant portions 26 to provide a chamber in the door which may be filled with insulating material 28, such as cork, mineral wool, or any other suitable insulating medium. This provides an insulated door with the defining edge portions 28 of the body member 27 being arranged to lie within the opening defined by the channel portions 15—16 of the hinge members 13.

The side defining portions 28 of the body member 27 have normally extending flange portions 29 which are secured, as by welding or the like, to the reentrant edges 26 of the door member. In order to seal the door with respect to the hinge, suitable sealing means 30 which may be in the form of rubber tubing if so desired, is secured to the inner face of the flange portions 29 by cementing or in any other suitable manner, and when the door is in closed position, engages the face portions 32 which connect the channel portion of the movable hinge member with the reversely curved portions 12. Disposed inwardly of the door opening and secured to the inner face of the flange portions 29 are angle shaped strips 33 which project normal to the plane of the door member 25 and parallel to the side wall portions 28 of the body member 27. The members 33 are therefore adapted to enter into the channels formed between the portions 15 and 16 of the hinge, and are so constructed as to have diagonally extending ends 34 which engage the diagonal edges 20 of the spacing portions 19 of the hinge member so that the door is wedged into position in the channel to thereby prevent any relative vertical movement between the door and the hinge member 13. This wedging action insures the door against vertical movement or vibration within the hinge member 13, and also serves to support the weight of the door upon the hinge member, and consequently when the hinge is swung around the pin 10, the door is entirely carried thereby.

It will be noted that the wall portions 16 of the hinge member 13 are provided adjacent their longitudinal center with an outstruck boss portion 35, which portion is provided with a cam face 36 and an arcuately curved surface 37. A suitable latch dog 38 is carried within the body member 27 by the housing 39, and is mounted upon the pin 40 for pivotal movement in accordance with the operation of the control plunger 42, which plunger extends through the housing 39 and outwardly through the door 25 to an operating button 43 secured to the end thereof. A suitable spring 44 is biased within the housing 39 against the extending leg portion 45 of the dog 38 so as to normally urge the dog outwardly of the door 46 in the side wall portion 28 of the body member 27. The plunger is provided with a suitable stop 47 limiting this outward movement. Inward movement of the plunger 43, as shown in Figure 5, results in pivoting the dog 38 about the pin 40 in a counterclockwise direction, thereby moving the latch or dog 38 into the housing 39 and out of engagement with the

arcuate surface 37 of the latch boss 35. Thus, when the plunger 43 is pushed inwardly, the latching engagement between the dog 38 and the wall 16 of the hinge member is released and the door 25 is then free to move outwardly with respect to the side edge of the door opening, withdrawing the member 33 from the channel of the hinge member and thus allowing the door to swing upon the vertical hinge pin 10 at the opposite side edge which is still retained in locked position.

When the door has been swung to its open position, the hinge member from which the particular door edge has been released remains in the position shown in Figure 1, and in such position, is adapted to receive the projecting portion 33 of the door in the channel thereof as the door is swung toward closed position. Swinging of the door into closed position results in compression of the member 30 against the portion 32 of the hinge member, and at the same time, the projecting edge of the dog 38 rides up the cam surface 36 of the boss 35 until it passes the end of this surface and swings over into abutting engagement with the arcuate surface 37. When moved into this position, the spring pressure results in tight abutment or latching engagement therebetween, holding the door with the member 33 securely locked to the hinge member. For purpose of effecting a positive seal, suitable resilient sealing means 48 is provided between the outer edge of the wall 16 of the hinge member and the member 33, the sealing means being slightly compressed when the wall edge engages therewith. Similarly, a resilient strip 49 is disposed along the back surface of the channel formed by the walls 15 and 16 to be engaged by the forward edge of the angle member 33 carried by the door, thereby sealing the entire hinge structure and door against leakage either inwardly or outwardly therebetween.

It will therefore be apparent from an analysis of the structure shown in Figure 3 that when the right hand push button 43 is depressed, the latch 38 is removed from engagement with the abutment 35 and the door can then be swung about the left hand hinge pin 10 to move outwardly of the right hand hinge member 13, the left hand edge of the door being held in tight engagement with the left hand hinge member 13 during this swinging movement. Inasmuch as the member 33 is wedged into the channel of the left hand hinge member in such manner as to be prevented from vertical movement therein and is secured against outward movement therefrom by the latching engagement, it will be apparent that the left hand hinge member and member 33 at the left hand edge of the door move as a unit about the hinge pin 10 as a center during this door opening movement. It will be obvious that if the left hand button 43 were depressed, the entire end portion of the door would swing about the right hand hinge pin 10 in exactly the same manner. It is therefore believed apparent that I have provided a construction employing a channel shaped hinge member with a channel shaped door edge adapted to be latched into sealing engagement with the channel hinge portion to move as a unit therewith, or adapted to be released therefrom and swing outwardly away from the hinge, depending upon the operation of the latching mechanism.

The provision of the sealing means insures positive closing of the door with reference to the door opening to prevent any leakage about the

edges of the door through the hinge member. The resiliency of such sealing means insures that the latching engagement will be effective to hold the edges of the members 16 and 33 in depressed position within the associated sealing means 48 and 49, thereby providing a firm seal and at the same time providing some resilience tending to spring the member 33 out of the hinged channel when the latch is released. Additional resilience is provided for this purpose by the tubular sealing member 30 carried on the inner defining edge of the door which engages about the defining edges of the door opening.

Also, it will be apparent that by providing a hinge which extends entirely along the vertical edge of the door opening a rigid construction with equalized stresses upon all portions of the hinge pin is produced, and consequently there is little or no danger of the hinge pin being over stressed or bent during operation of the mechanism.

In the embodiment of the invention shown in Figures 6 to 10, inclusive, a modified structure is provided in which a vertically extending hinge pin 50 is supported in position by stationary hinge bracket members 52 which are recessed into the defining edges 51 of the door opening and rigidly secured therein by means of the screws 53 and 54. The member 52 is provided with a reversely curved portion 55 engaging about the hinge pin 50 for holding it in position. Corresponding members 52 are provided at the upper and lower edges of the door opening, and therefore form spaced vertical supports for the hinge pin.

35 Mounted upon the hinge pin intermediate the fixed supporting portions 52 is a hinge member, indicated generally at 56, having an elongated reversely curled portion 57 engaging about the hinge pin for pivoting the member 56 thereon. 40 The member 56 is provided with a portion 58 which extends along the outer face of the door opening and with a normally extending channel portion indicated generally at 59 comprising the walls 60 and 62 spaced apart at their rear edges by the transverse web portion 61. The channel portion 59 is adapted to lie against the vertical side of the door opening, and suitable sealing means may be interposed between the portion 58 of the hinge and the facing portion of the door opening if desired. Intermediate its longitudinal ends, the wall portion 62 of the channel 59 is cut away, as indicated at 63 to provide an opening in which is disposed a detent member 64 suitably secured as by means of the studs 65 to the inner wall portion 60 of the channel. The detent 64 is provided with an outwardly and rearwardly curved tongue 66 which projects into the plane of the wall portion 62, as shown in Figure 8. For purposes of adjustment, the member 64 may be provided with transverse slots in which the studs 65 are disposed, thereby allowing adjustment of the member 64 toward or away from the rear wall 61 of the channel. It will be apparent that this construction corresponds somewhat to the channel formed by the walls 15 and 16 of the channel portion of the hinge member 13 shown in Figures 1 to 5, and that the member 64 corresponds, to some extent, to the projecting abutment or boss 35 on the wall 16. The door member for the embodiment of the invention shown in Figures 6 to 10 includes an outer wall portion 70 which may be slightly convex, and which is provided with an inturned lateral edge portion

12 having a channel-shaped portion 13 projecting substantially normally to the plane of the door and adapted to extend into the channel 59 of the hinge. However, the channel portion 13 comprises a planar wall portion 14 and a wall portion 15 which flares slightly away from the plane of the wall 14 adjacent the open end of the channel. The channel portion 13 of the door is preferably formed of a sheet metal material which has some degree of resilience whereby the tapering shape of the channel 13 is adapted to have wedging engagement in the channel 59. This prevents lateral relative movement between the two channels, and insures a tight engagement when the channel 13 is introduced into the channel 59.

It will be noted from Figures 7 and 10 that the channel portion 13 of the door is cut away intermediate its ends to provide the horizontally extending surfaces 16 which are spaced apart a distance corresponding to the length of the member 64 carried upon the hinge. By this arrangement, when the door is swung to closed position, the edges 16 of the channel 13 engage the corresponding edges of the member 64 to provide a wedging engagement therebetween which locks the channel 13 against relative vertical movement within the channel 59. This corresponds to the wedging action produced between the edges 34 of the member 33 shown in Figure 2 and the diverging edges 20 of the spacing tongues 19 disposed in the channel 16 of Figure 1. Thus the door is held by the wedge shape of the channel 13 against relative lateral movement within the channel 59, and by engagement of the edges 16 with the member 64 is rigidly supported against relative vertical movement within the channel 59. Carried on the inner face of the door member 10 is a body member 18 which has a flange portion 19 secured to the re-entrant flange 12 of the door member 10, as by welding or the like, and which is spaced away from the door member 10 by reason of the intermediate flange portions 80 corresponding to the flange portions 28 of the body member 21 shown in Figure 3. Between the outer door member 10 and the body member 18 the door may be filled with insulating material, as described in connection with Figure 3.

A suitable latch mechanism, which may be of any conventional type and is shown only for purposes of illustration, is carried within the body member 18 by the housing 82, the latch dog 83 being of a type having the rear cam face 84 and being spring pressed normally outwardly of the flange 80. A suitable bell crank lever 85 pivoted within the door and actuated by the plunger 86 operates the latch to move inwardly or outwardly relative to the flange 80. When in normal latched position, the projecting end of the dog 83 is engaged on the rear edge of the tongue 66 of the member 64, and consequently locks the entire assembly in fixed position similar to the manner in which the latch 38 locks the assembly shown in Figure 5. Suitable sealing means 87 is interposed between the flange 12 of the door and the flange portion 58 of the hinge member 56, and corresponding sealing means is disposed within the rear end of the channel 59, as indicated at 88, to be engaged by the forward projecting end of the channel 13. This provides effective sealing between the hinge and door edge. When it is desired to release the door, the plunger 86 is pulled outwardly, moving the latch member 83 into the body member 18 and out of

engagement with the member 64. As a result, the latching engagement is released between the door edge and the hinge member 56, and the door can then be pulled outwardly from this hinge member to swing about its opposite pivot at the opposite side edge for opening movement. It is to be understood, of course, that a similar hinge structure and door edge arrangement is provided at the opposite side of the door opening, and that the structure functions in substantially the same manner as described in connection with the embodiment shown in Figures 1 to 5, wherein, release of the latching member at one door edge causes the door to swing about the hinge arrangement at its opposite vertical edge.

It will be noted that in both forms of the invention thus far described, suitable sealing means is provided which are resilient in nature such that they tend to swing the door slightly open upon release of the latch. At the same time, the angularity of the surfaces 20 and 34 of the first embodiment and of the ends of the member 64 and the surfaces 16 of the second embodiment produce a component of the weight of the door also tending to force the door open. Thus, release of the latch, in effect, starts the door moving toward open position.

It will also be apparent that with the constructions described thus far, all parts thereof may be made of simple stampings, and since they are substantial duplicates at both sides of the door opening, only one stamping die for each of the parts is required. This produces economy in manufacture and simplicity in assembly. The adjustability of the latch member 64 in Figure 6 is desired for the purpose of insuring that the sealing means will be properly compressed when the latch member is engaged. It is also to be understood that, while the latch members have been shown more or less diagrammatically and merely for the purpose of describing the hinge mechanism, conventional latches of the type now in use can be readily employed and adapted for this purpose, and the invention is not intended to be limited to the particular type of latching mechanism disclosed.

Referring now to the embodiment of the invention shown in Figures 11 to 13, a vertical edge of a door opening is indicated generally at 100 and is provided with a recessed portion 102 which extends forwardly toward the door face to meet with a correspondingly recessed portion 103 formed in the defining face 104 of the door opening. Disposed within the recess 103 is a hinge supporting member 105 which may be of the same type as the member 7 of Figures 1 to 5, and is provided with a reversely curled portion 106 engaging about the hinge pin 107 at spaced portions along the pin which extends vertically substantially in the plane of the surface 104. A hinge member 108 is provided with correspondingly curled portions 109 which engage intermediate portions of the hinge pin 107, the hinge member 108 having the normally extending flange or wall 110 lying along the defining surface of the recess 102. At its inner end the wall 110 is provided with a normally extending transverse portion 112 and terminates in the angularly extending flange portion 113, thereby defining a wedge or tapering shaped channel 114 disposed substantially in the plane of the side wall opening. It will be apparent that the channel portion 114 of the member 108 is adapted to swing about the pin 107 as a center, and suit-

able sealing means 115 is interposed between the member 108 and the member 105 to seal this portion of the structure. The member 105 is, of course, permanently secured in the recess 103. Secured to the transverse wall 112 of the channel 114 are one or more spring members 116 which are mounted by means of rivets 17 or the like on the inner face of the transverse wall 112, and project into the channel for a purpose to be described hereinafter.

The upper and lower edges of the wall 113 are bent at right angles to the plane of this wall and also at converging angles with respect to the horizontal to provide converging surfaces 118 at the upper and lower ends of the channel, the converging surfaces 118 terminating in normally extending tabs 119, which are welded or otherwise secured to the upper and lower ends of the wall 110 to provide an enclosed channel having the converging surfaces at the upper and lower ends thereof corresponding to the diagonal surfaces 28 of the tabs 19, which space the walls 15 and 16 apart in the embodiment of the invention shown in Figures 1 to 5, inclusive.

The door member for the closure in the form of the invention shown in Figures 11 to 13 may comprise an outer sheet portion 120 having the reentrant edges 122 and an inner body portion 123 having the normally directed edges 124 corresponding to the edges 28 of the body member 27, and also having a flanged end 125 parallel to and spaced inwardly of the outer wall portion 120. Between the flange 125 and the reentrant edge 122 there is provided a channel shaped stamping 128 having vertically extending parallel flange edges 127 and 128 secured respectively to the flanges 122 and 125 for permanently and rigidly securing the member 126 to the door. The channel portion of the member 126 comprises the walls 129 and 130, which are parallel to and adapted to be disposed within the walls 110 and 113. The two walls 129 and 130 are connected together by a transverse wall portion 132 which, when the door is in closed position engages against the spring 116 and deforms this spring to some extent. The wall 113 of the channel 114 is provided with a projecting boss 135 having the planar inclined surface 136 and the arcuate cam surface 137 corresponding to the surfaces 36 and 37 of the member 35 of Figure 5. A suitable latch member 38 of Figure 5 is adapted to ride up the inclined surface 136 while the door is being closed, and to then move into engagement with the arcuate surface 137 for latching the door in closed position.

Due to the spring pressure of spring 116 on the transverse wall 132, it will be apparent that upon release of the latch 38 from engagement with the surface 137, the spring 116 will kick the door edge outwardly and start it upon its swinging movement about the remotely disposed hinge pin. However, when the latch remains in position, the channel portions 126 and 114 are telescoped together in tight engagement, it being understood that the upper and lower ends of the channel portion 126 are tapered in accordance with the taper of the surfaces 118, and consequently the door edge is held both vertically and laterally firmly within the hinge member 108 so that upon release of the remote latch, the door edge and hinge member swing as a unit about the pin 107. It is preferable that the flange portion 127 of the channel 126 carry a suitable sealing strip 140 for sealing the hinge structure, the same as described in connection

with previous embodiments. By reason of the inclined surface of the walls 113 and 130, it will be noted that the channel 126 is free to move outwardly of the channel 114 and there will be no binding action produced because of the increasing angularity between the door and the door opening. By having the taper on this side of the door opening, the opening and closing of the door to provide for the telescoping movement of the two channel members carried by the door and hinge, respectively, is facilitated.

If desired, a suitable safety spring pressed plunger 145 can be carried upon the wall 129 and normally urged through an opening 146 therein into a detent opening 147 in the wall 110 to insure against release of the door edge from the hinge structure when the opposed or remote latch has been released. A suitable stud 148 normally holds latch 145 out of engagement with opening 147 when in door-closed position.

The latch structure for use with the embodiment of the invention shown in Figures 11 to 13 may correspond to that shown in detail in Figures 1 to 5, or may be any other equivalent latch structure suitable for the purpose.

In Figure 14 is disclosed the present invention as applied to a domestic refrigerator structure now on the market. In this embodiment, the side wall 150 of the refrigerator has the reentrant flanges 152 defining one lateral surface of the door opening, this flange being connected through the non-metallic fiber or plastic strip 153 to the inner lining wall 154 of the refrigerator cabinet.

Mounted on the wall 152 in a manner such as described in the previous embodiments is a hinge pin 155 having the hinge member 156 pivotally mounted thereon. The member 156 has a planar portion 157 overlying the outer defining surface of the wall 150 and an inwardly bent channel portion 158 over which is molded the vertically extending bar 159 of a suitable hard setting plastic material, having the outwardly projecting converging guide walls 160. This bar extends substantially the full height of the door opening and is rigidly secured to hinge member 156 for conjoint movement therewith.

The closure or door has the outer defining sheet metal wall 162 provided with the inturned edge portion 163 to which is secured the resilient sealing strip 164 of conventional design. At its end the portion 163 is flanged, as at 165, to provide a support for a sealing means 166 and a non-metallic spacing strip 167 connected to the inner door liner 168.

Secured to the door edge 163 between sealing strip 164 and sealing means 166 is a vertically extending channel-shaped trough member 169 secured at its base by screws or other detachable means to the portion 163 of the door. The side walls 170 of the channel member 169 are angled to mate with and receive therein the outwardly projecting wedge portion 160 of bar 159, thereby interlocking the door edge and hinge member against relative lateral movement. Suitable means at the opposite ends of channel member 169 engage the opposite ends of the bar when in interlocking engagement to hold the door edge against relative vertical movement. This may correspond to the ends 118 of the channel 112 of Figure 11, or its equivalent.

In order to maintain the door edge and hinge member 156 in rigid interlocking engagement, the door at each of its lateral edges is provided

with latch means comprising a plunger 172 normally urged outwardly and having the cam face 173 which forces the plunger inwardly as the door is being closed. This face rides over the outer wall 160 of bar 159 until after it passes the corner 174, whereupon the latching face 175 of the plunger engages against the rear face 176 of the bar 159, holding the channel member 169 firmly in engagement with bar 159. The latching means may of course be of any desired form capable of operating in this manner.

It is to be understood that both lateral edges of the door and the opening are constructed in the manner described, and provided with corresponding hinging means, so that the door may be selectively opened about either door edge.

With the construction shown in Figure 14, the strips 153 and 161 prevent thermal transmission between the outer and inner metal walls, and by making the bar 159 of a plastic no thermal transmission or condensation is produced on the hinging means. Of course, if so desired, a metal member may be substituted for the bar 159 without in any way changing the construction or operation.

It is therefore believed apparent that I have provided a novel type of hinging structure for opposed vertical edges of a door or closure member, whereby the door can be selectively swung for opening and closing movement about either edge with the opposite edge locked in tight hinging engagement with hinge means of simple but rugged design. Also, the present construction will allow removal of the entire door if and when desired.

It will also be apparent that the present construction lends itself admirably to use of present types of refrigerator door structures, and also provides adequate means for sealing the structure to prevent entrance of heat or passage of gases either into or out through the hinge and door edge engagement.

I am aware that various details of construction herein described and illustrated may be varied without in any way departing from the underlying principles of the present invention, and I therefore do not intend to limit myself except as defined by the scope and spirit of the appended claims.

I claim:

1. The combination, in a structure having a generally rectangular door opening and a rectangular door for closing said opening having defining edges overlying said opening, of hinge means pivotally supported along the vertical edges of said opening and having movable portions extending vertically within said opening for substantially the entire vertical extent thereof and lying against the vertical sides of said opening, hinge engaging means extending normally to and secured to the inner face of said door having tongue and groove interlocking engagement with said hinge portions for substantially the entire length thereof, and latch means carried by said door adjacent each vertical edge thereof and selectively engageable with said hinge portions for locking said normally extending means on said door in said hinge portions.

2. The combination of claim 1 wherein said hinge portions comprise vertically extending outwardly directed channels having closed upper and lower ends.

3. Means for hinging a door to swing about either vertical edge of a rectangular door opening comprising a hinge element pivotally secured

to each of the vertical edges of the door opening and having a reversely bent portion lying within the defining edge of the opening and forming an outwardly directed channel extending substantially the full length of said opening, a second hinge element secured to the door having a normally directed flange at each vertical edge of the door adapted to extend into said channel when the door is closed, means on said channel forming a lateral abutment substantially midway of the length thereof, and spring controlled latch means carried by said door adjacent each vertical edge engageable with said abutment for locking said door edge to said channel for conjoint pivotal movement with the associated hinge element.

4. The combination of claim 3 further characterized by inwardly converging wedge surfaces on the hinge element engageable by corresponding wedge surfaces on said door flange for maintaining the door flange against vertical movement relative to said channel when engaged therein.

5. The combination of claim 3 further characterized by the provision of resilient means in the base of each of said channels for urging the door flange outwardly therefrom upon the release of said latching means.

6. Means for mounting a door to swing about either vertical edge of a door opening comprising a hinge element pivotally mounted upon the front of each of the defining vertical edges of said opening, said element extending substantially the full length of said opening and having a normally extending flange portion disposed within the opening, hinge means on the door having vertically extending hinge elements projecting normal to the plane of the door adjacent each vertical edge thereof, one of said hinge elements at each side of the opening including a channel shaped portion adapted to receive the other cooperating hinge element, means for latching said elements together for conjoint swinging movement about the pivotal mounting of said first-named hinge element when the latching engagement at the opposite lateral edge of the door opening is released.

7. The combination of claim 6 wherein the cooperating elements at each side of the opening have wedge surfaces engageable in latched position to prevent relative vertical movement therebetween.

8. The combination of claim 6 further characterized by means locking said associated elements together independently of said latching means upon swinging movement of the door about the associated edge.

9. Means for mounting a door to swing about either edge of a door opening comprising a hinge element pivotally mounted at each vertical edge of the opening and having a portion disposed within and lying against the side of said opening, said portion extending substantially the full length of said opening and including a rigid vertically extending non-metallic member presenting an outwardly directed laterally converging surface, the side edges of the door being extended to overlie said element, cooperating hinge elements on the door edge having an inwardly opening channel at each vertical edge of the door in alignment with and coextensive with said portion of said first hinge element, said channel being wedge-shaped to fit over said non-metallic member when the door is in closed position, and latching means at each lateral edge of the door

engageable with said first hinge element for conjoint swinging movement when the latching means at the opposite door edge is released.

10. Hinge means for optionally hinging a door to swing about either vertical edge of a door opening, comprising a vertically extended hinge element pivoted on the front face of each vertical defining edge of said opening and including a wedge-shaped vertically extending portion offset into said opening and formed of a heat insulating material, a vertically extending channel-shaped hinge element rigidly secured to the inside surface of the door adjacent each vertical edge thereof, latch means carried by the door, and a latch receiving surface formed on the offset portion of said first hinge element whereby said latch holds said channel-shaped hinge element and said wedge-shaped portion of said first hinge element in interlocked engagement for swinging movement about the pivot support of said first hinge element.

11. Means for hinging a door to swing optionally about either vertical edge of a corresponding door opening, comprising hinge elements secured to the inner surface of the door adjacent each vertical edge thereof and each

5 element including a channel-shaped portion of substantial vertical extent opening toward the door opening, hinging element pivotally mounted on vertically extending pivots on the front surface of the vertical walls defining the vertical edges of the door opening and in line with the outer defining vertical edges of the door, said second hinging elements each including a flat portion extending laterally toward each other and carrying vertically extending wedge elements adapted to be engaged in said channel-shaped portions when the door is in closed position, and latching means carried by the door adjacent each of said hinge elements and including a latch member engageable with the associated wedge element to maintain it engaged in said channel-shaped portions, said latching means being selectively operable to release said hinge and hinging elements at one side of said door for opening said door by pivotal movement about the opposite hinge element pivot.

15 20 25 12. The hinge means of claim 11 further characterized in that one of each pair of interengaging hinge elements is non-metallic and of heat insulating character.

CHARLES E. CAMPBELL.
